(57) CLAIM

I claim the ornamental design for a footwear upper portion, as shown and described.

DESCRIPTION

FIG. 1 is a perspective view of a footwear upper portion, showing my new design;

FIG. 2 is a right side view thereof, the left side view being a substantially mirror image of the right side view; and, FIG. 3 is top view thereof.

The broken line showing in the figures of the sole and other parts of the footwear upper is for illustrative purposes only and forms no part of the claimed design.
